UNITED STATES PATENT OFFICE.

JAMES H. BARLOW, OF LEWISTON, MAINE, ASSIGNOR TO DRAPER CORPORATION, OF HOPEDALE, MASSACHUSETTS, A CORPORATION OF MAINE.

FEELER-MOTION FOR LOOMS.

1,362,107.

Specification of Letters Patent. Patented Dec. 14, 1920.

Application filed October 26, 1918. Serial No. 259,740.

To all whom it may concern:

Be it known that I, JAMES H. BARLOW, a citizen of the United States, and a resident of Lewiston, in the county of Androscoggin and State of Maine, have invented an Improvement in Feeler-Motions for Looms, of which the following description, in connection with the accompanying drawings, is a specification, like characters on 10 the drawings representing like parts.

The invention to be hereinafter described relates to looms and more particularly to feeler motions to effect a change in the operative condition of the loom when the 15 filling reaches substantial exhaustion but prior to complete exhaustion.

In weaving certain kinds of fabrics using a plurality of shuttles much delay and loss of production occur when any one of the 20 shuttles fails to lay a complete pick in the shed. In such event, the loom must be stopped and turned back to "find the pick" as it is called. This is necessary because otherwise the pattern effect would be destroyed and the resulting fabric be imperfect. The difficulty of turning back to "find the pick" becomes emphasized when, in addition to the figuring effect produced by two or more shuttles, the warps are also pattern 25 controlled, as by a "jacquard."

An important feature of the present invention, therefore, consists in providing two feelers, one at each side of the loom, which act alternately to feel for and detect the condition of the filling in different shuttles, and upon detection of substantial exhaustion by either feeler set a train of mechanism in action to change the operative condition of the loom. The change in the operative condition 30 of the loom may be effected by replenishment of filling or it may be by stopping the loom. In either case, however, the difficulties and objectionable delays and loss of production due to "finding the pick" when 35 only a partial shot of filling is laid in the shed, are overcome.

Another important feature of the invention consists of two feelers, one at each side of the loom, coöoperating with two shuttles, 40 one feeler acting in conjunction with one of the shuttles at one side of the loom and the other feeler acting in conjunction with the other shuttle at the opposite side of the loom.

55 The above and other features of the inven-

tion and novel combinations of parts will be best made clear from the following description and accompanying drawings of a good practical form of the invention and its various novel characteristics.

60

In the drawings:

Figure 1 is a front view of a loom showing the present invention applied thereto, some of the parts being broken away and others omitted for clearness of illustration; 65

Fig. 2 is a perspective view of one end of the loom;

Fig. 2^a is a detached detail;

Fig. 3 is an enlarged elevation showing more particularly a feeler and its connec- 70

tions;

Fig. 4 is a cross-section on line 4—4, Fig. 3;

Fig. 5 is a cross-section on line 5—5, Fig. 3;

75

Fig. 6 is a section on line 6—6, Fig. 3;

Fig. 7 is a perspective view showing the relation of parts when one of the feelers detects substantial exhaustion of filling.

The invention will be hereinafter described in connection with a loom for weaving cloth wherein two shuttles are employed, one carrying filling for weaving the ground and the other a filling for weaving a figure. Likewise, it may be that two sets of warp may be employed, one set for the ground being controlled by a usual heddle motion and the other set for the figure or pattern being controlled by a jacquard. Looms of this general type are employed for weaving 80 figured cloth, such as counterpanes and the like, and being well understood by those skilled in the art no detailed description of the general loom parts and shedding mechanism is necessary. In looms of this 85 type a two cell shuttle-box is employed at each end of the lay, one shuttle coöoperating with the top cell at one side of the loom and the bottom cell at the opposite side of the loom, and while the present invention is ad- 90 vantageously employed in connection with such type of loom, it may also be used with good results in other forms of looms, consequently the invention is not restricted in this respect.

95

The loom frame may be of suitable character for supporting operating parts and as shown comprises the side frames 1 at the lower portion of which are mounted the lay swords 2 as usual for carrying at their up- 100

105

110

per portions the lay 3. The lay is given its usual reciprocating movements to beat up the filling by connection with the usual drive shaft or otherwise as conditions may dictate, and as the construction thus far described is well known and understood, further elucidation is unnecessary.

Mounted at each end of the lay is a shifting shuttle-box which, in the present instance of the invention, comprises two cells and suitable mechanism is employed for shifting the shuttle boxes to bring the appropriate shuttle on the line of the race. In the present instance the lay 3 has mounted thereon at each end the shuttle box guides 4 and 5 between which is mounted the shifting shuttle box 6 having the two cells 7 and 8 as clearly indicated in Fig. 1. Each of the shifting shuttle boxes 6 is connected with a rod 9, the lower portion 10 of which passes through a guide 11 as indicated in Fig. 2 and at its lower end has a projection 12 connected by an adjustable link 13 with a shuttle box shifting lever 14 pivotally mounted at 15 and suitably actuated at desired times by means of a cam 16 secured to the shaft 17, said cam acting upon a roll 18 mounted on the shifting shuttle box lever 14 as indicated in Fig. 2a. The parts just described are the usual construction and while they present one good form of means for effecting the shifting movement of the shuttle boxes, it is to be understood, of course, that such shifting movement may be effected by variously contrived means.

Pivottally mounted at 19, Figs. 1 and 2, is the usual picker stick 20, one at each side of the loom, such picker sticks being actuated by suitable means through the lug straps 21 to pick the shuttle. The picker 22, Fig. 2, is mounted for sliding movement on the picker rod 23 as usual under the impulse of the picker stick, one of such being, of course, associated with each shuttle box. These parts may be of usual construction.

In a loom of the type under consideration wherein two shuttles are employed, one carrying a ground and the other a figuring filling thread, one of said shuttles coöperates with the top cell of the shuttle box at one side of the loom and with the lower cell of the shuttle box at the opposite side of the loom, the effect being that the shuttle carrying the ground filling thread will, at one side of the loom, be received into the top cell of the shuttle box while the shuttle carrying the figuring filling thread will be received into the top cell of the shuttle box on the opposite side of the loom. The present invention, therefore, contemplates a feeler at each side of the loom, one to detect the condition of the ground filling thread in the shuttle, and the other to detect the condition of the figuring filling thread in the shuttle, the construction being such that should either feeler de-

tect substantial exhaustion of filling in the shuttle with which it coöperates, it will set in action a train of mechanism to change the operative condition of the loom and avoid laying of partial picks and the consequent necessity of turning the loom back to "find the pick."

In the present instance of the invention the two feelers, one at each side of the loom, are mounted above their respective shuttle boxes and feel downwardly through the top of the shuttle, and while this construction is found to be advantageous inasmuch as it does away with the necessity for slotting the wall of the shuttle box and shuttle for the entrance of the feeler, it is to be understood that the invention is not restricted in this respect. In carrying this feature of the invention into effect in the present instance, a feeler support 24 is mounted at each end of the lay above each of the shifting shuttle boxes and mounted on the feeler supports 24 are the two feelers 25 and 26 which, as the shuttle boxes are raised feel into the respective top cells of the boxes to detect the condition of the filling in the shuttles. The feelers 25 and 26 may be variously contrived but in the present instance of the invention they are of the impinging and penetrating type, the general construction of such feelers being indicated in Figs. 3 and 6. Referring to said Figs. 3 and 6, the feelers comprise a feeler stand 27 appropriately secured to the respective feeler supports 24 one at each side of the loom. Mounted for reciprocating movement in the feeler stand 27 is the slide 28 the lower portion 29 of which constitutes an impinging member. Extending through the slide 28 at its end portion is the penetrating feeler member 30 having an angular portion 31 adapted to bear against a finger 32 pivoted at 33 on the feeler slide 28. The finger 32 is normally held in its inoperative position by a plunger 34 normally under the influence of a spring 35, the construction being such that should a working supply of filling be present in a shuttle when the feeler performs its detecting function, the penetrating member 30 will sink into the filling and then the impinging member 29 will be engaged by the filling mass and the slide 28 will be lifted as the shifting shuttle box is raised to its upper position to bring the lower cell of the shuttle box in line with the race. If, however, the filling should be substantially exhausted when the feeler performs its detecting function as indicated in Fig. 6, the penetrating member 30 will engage the more dense mass of the filling carrier or bobbin 36 contained in the shuttle occupying the upper cell of the shuttle box and will be moved upwardly thereby to deflect the finger 32 or move it against the action of the spring plunger 34 into an operative position and upon further

110
115
120
125
130

upward movement of the shuttle box the finger 32 will act through a train of mechanism to cause a change in the operative condition of the loom. In the present instance 5 of the invention this change in the operative condition of the loom is utilized to effect loom stoppage.

Pivottally mounted at 37 adjacent each of the feelers, Fig. 3, is a controller 38 formed 10 as a lever one end 39 of which is normally out of the path of the finger 32 of the feeler when the feeler performs its detecting function and a working supply of filling is present in the shuttle, but when the filling has 15 become substantially exhausted and before complete exhaustion, the finger 32 will engage the arm 39 of the controller and move it to actuate a train of mechanism to effect the desired change in the loom operation.

20 Pivottally mounted at 40 and connected to each of the controllers or levers 38 is a pin or plunger 41 which extends through a block 42 secured to the feeler support 24.

Each of the feeler supports 24 is provided 25 with a slot 43 extending longitudinally thereof and extending into each of said slots is a pin or lug 44 which, as the lay performs its reciprocating movements, is caused to slide back and forth in said slots and past 30 the position of the pins 41. Each of the pins 44 is appropriately mounted upon a slide 45 which is guided in its reciprocating movements by bridge pieces 46 as more clearly represented in Figs. 4 and 5.

35 Pivottally supported on the fixed part of the loom frame, as for instance the breast beam 47, near the opposite ends thereof is a rock-shaft 48 each of which carries an arm 49 and links 50 connect the arms 49 at opposite sides of the loom with the slides 45. Springs 51 may be employed to normally maintain the rock shafts 48 with their respective fingers or arms 49 in normal position, the construction being such that as 40 the lay is reciprocated toward and from the front of the loom or the breast beam 47, the slides 45 will be reciprocated longitudinally of the feeler supports 24. If, however, either of the pins 41 is depressed into the 45 path of either of the pins or lugs 44 on the slides 45, the reciprocating movement of one of the slides 45 will be interrupted or retarded with the effect that as the lay moves backward the rock-shaft 48 will be rocked. Advantage is taken of this rocking movement of either of the rock-shafts 48 to change the operative condition of the 50 loom, as will more fully appear.

Extending from the breast beam 47 at one 60 side of the loom, at the right in the illustrated form of the invention, there is a shipper bracket 52 having a slot 53 in which is movable the shipper 54. The shipper 54 may be operatively connected with the source 65 of power as, for instance, a belt shipper or

clutch as usual for stopping the loom when the shipper 54 is moved longitudinally outward in the slot 53 of the shipper stand. The shipper stand has a shipper holding notch 55 which is adapted to hold the shipper 70 in position with the loom in operative connection with the source of power as usual and suitable spring means may be employed to throw the shipper longitudinally of the slot 53 as usual when the shipper is 75 detached from its holding notch.

Pivottally mounted on the shipper stand 52 at one side of the loom at 56, Fig. 7, is a knock-off lever 57 having a curved end portion 58 adapted to be engaged by a depending arm 59 extending from the rock shaft 48 at that side of the loom. The knock-off lever 57 normally rests against the shipper 54 when the latter is in its holding notch, the construction being such that 80 should the rock-shaft 48 at that side of the loom be turned or rocked under the conditions hereinbefore described, the finger 59 will ride along the inclined end 58 of the knock-off lever 57 and detach the shipper 90 lever from its holding notch and, perforce, effect loom stoppage.

Extending transversely of the loom adjacent the breast beam 47 is a slide 60 mounted for sliding movement in a support 61 adjacent the shipper lever 54, as indicated in Fig. 1. The slide 60 adjacent the shipper lever 54 is provided with a notched detent 62 as indicated by dotted lines in Fig. 7, said detent having an inclined portion 63 which, when moved to the left, Fig. 7, is adapted to engage and move the shipper lever 54 from its holding notch. The slide 60 at the side of the loom opposite the shipper lever 54, as shown by 105 Fig. 1, is provided with a lug 64 adapted to be engaged by the finger 65 extending from the rock shaft 48, the construction being such that if the rock-shaft 48 be rocked owing to interruption in the sliding movement 110 of the slide 45 at that side of the loom, the arm 65 will engage the lug 64 of the slide 60 and move it lengthwise to effect disengagement of the shipper 54 from its holding notch thereby effecting loom stoppage. 115

From the construction described it will be apparent that should either one of the feelers at either side of the loom detect substantial exhaustion of filling in the shuttle with which it coöperates and thereby arrest movement of the slide 45 associated therewith, a change in loom operation will result, such change in the present instance of the invention bringing the loom to rest.

It is desirable in a loom of the character 125 described that after the loom has been stopped the attendant may be enabled to start the loom again from either side of the loom and to this end the slide 60 has connected thereto at the side of the loom op- 130

posite the shipper handle, a hand lever 66 pivotally mounted at 67 to a bracket extending from the breast beam 47 and jointed at 68 with the slide 60. The detent 62 at the 5 opposite end of the slide 60 has an abrupt lug 69 between which and the inclined portion 63 of the detent the shipper 54 is embraced, the construction being such that should the hand lever 66 at the left hand 10 side of the loom, Fig. 1, be moved clockwise, Fig. 1, the shipper handle 54 will be drawn into its holding notch and there held to maintain the loom in operative condition. Likewise, at the right hand side of the loom 15 as indicated in Fig. 1, the shipper 54 may be directly manipulated by the attendant to start the loom.

While the above described construction forms a good practical embodiment of the 20 present invention, various changes may be made within the true scope thereof as applicant believes himself to be the first in this art to provide two feelers, one at each side of the loom, each to coöperate with one 25 of a plurality of shuttles to effect a change in the operative condition of the loom when either feeler detects substantial exhaustion of filling in the shuttle with which it co-operates.

30 Claims:

1. In a loom, the combination of the lay, 35 shifting shuttle-boxes at opposite ends of the lay each having two cells for shuttles containing different kinds or character of filling, a feeler at each side of the loom, one of which enters and detects the condition of filling in one of the shuttles when it is inactive at one side of the loom and the other of which enters and detects the condition of filling in the other shuttle when it is inactive at the opposite side of the loom, and means common to both feelers and rendered effective for stopping the loom upon 40 detection of substantial exhaustion of filling 45 by either feeler.

2. In a loom, the combination of the lay, shifting shuttle-boxes at opposite ends of the lay each having two cells for shuttles containing different kinds or character of 50 filling, a feeler mounted on the lay at each side of the loom, one of which enters and detects the condition of filling in the inactive shuttle at one side of the loom and the other of which enters and detects the condition of filling in the inactive shuttle at the 55 opposite side of the loom, and means actuated by either feeler for stopping the loom upon detection of substantial exhaustion of filling by either feeler.

60 3. In a loom, the combination of the lay, a shifting shuttle-box at opposite ends of the lay for containing a plurality of shuttles, a feeler at each side of the loom, one of which feels into and detects the condition 65 of the filling in one of the shuttles and the

other of which feels into and detects the condition of the filling in the other shuttle, and means actuated by the feeler at either side of the loom for stopping the loom when either feeler detects substantial exhaustion 70 of filling in the shuttle into which it feels.

4. In a loom, the combination of the lay and a two cell shifting shuttle-box at each side of the loom, a feeler at each side of the loom, one to always feel into and detect 75 the condition of the filling in one of the shuttles at one side of the loom, and the other to always feel into and detect the condition of the filling in the shuttle at the opposite side of the loom, and means ren- 80 dered effective for stopping the loom upon detection of substantial exhaustion of filling and prior to complete exhaustion by either feeler.

5. In a loom, the combination of the lay, 85 a shuttle-box at each end of the lay having two cells, a feeler at each side of the loom, one to coöperate always with one of the shuttles when it is at one side of the loom and the other to coöperate always with the 90 other shuttle when it is at the other side of the loom, means for alternately causing the feelers at opposite sides of the loom to feel into and detect the condition of the filling in a shuttle, and means rendered effective to 95 stop the loom when either feeler detects approaching exhaustion of filling.

6. In a loom, the combination of the lay, a shifting shuttle-box at each end of the lay, a feeler at each side of the loom, and 100 means rendered effective by shifting movement of the shuttle-boxes to cause first one feeler at one side of the loom and then the other feeler at the opposite side of the loom to feel for filling in a shuttle, and means 105 at one side of the loom actuated by either feeler to stop the loom when the filling is substantially exhausted.

7. In a loom, the combination of the lay, a shifting shuttle-box at each end of the 110 lay, a feeler at each side of the loom movable with the lay, and means rendered effective by shifting movement of the shuttle-boxes to cause first one feeler at one side of the loom and then the other feeler at the 115 opposite side of the loom to feel for the filling in a shuttle, and means at one side of the loom actuated by either feeler to stop the loom when the filling is substantially exhausted.

8. In a loom, the combination of the lay, a shifting shuttle box at each end of the lay, a feeler at each side of the loom mounted on the lay above the shuttle-box, and means rendered effective by shifting 125 movement of the shuttle-boxes to cause first one feeler at one side of the loom and then the other feeler at the opposite side of the loom to feel for the filling in a shuttle, and means at one side of the loom actuated by 130

- either feeler to stop the loom when the filling is substantially exhausted.
9. In a loom, the combination of the lay having a shifting shuttle-box at each end for a plurality of shuttles, a feeler at each side of the loom, one of which always feels for the filling in a shuttle when it is at one side of the loom, and the other of which always feels for the filling in another shuttle when it is at the other side of the loom, and a single means controlled by either feeler to stop the loom when either feeler detects substantial exhaustion of filling. 70
10. In a loom, the combination of the lay, a shuttle-box at each end of the lay having cells for a plurality of shuttles, a feeler at each side of the loom to feel into a different shuttle and detect the condition of the filling, and a single means rendered effective 75 to stop the loom when either feeler detects substantial exhaustion of filling in either shuttle.
11. In a loom, the combination of the lay, a shifting shuttle-box at each end of the lay having two cells, a feeler at each side of the loom, one to feel into one shuttle and the other to feel into the other shuttle, and means common to both feelers to stop the loom when either feeler detects substantial 80 exhaustion of filling. 90
12. In a loom, the combination of the lay, a shifting shuttle-box at each end of the lay for a plurality of shuttles, a feeler at each side of the loom to feel for the filling first in one shuttle and then in another as such shuttles are moved to inactive position, and a single means at one side of the loom to stop the loom when either feeler detects substantial exhaustion of filling. 95
13. In a loom, the combination of the lay, a shifting shuttle-box at each end of the lay for a plurality of shuttles, a feeler mounted above the shifting shuttle-box at each side of the loom to feel for the filling first in one shuttle and then in another as such shuttles are moved to inactive position, and means common to both feelers to stop the loom when either feeler detects substantial exhaustion of filling. 105
14. In a loom, the combination of the lay, a shifting shuttle-box at each end of the lay having two cells, the upper cell at one side of the loom and the lower cell at the opposite side of the loom working with the same shuttle, a feeler at each side of the loom to feel into the shuttle in the upper cell of the shuttle-box, and means rendered effective to stop the loom when either feeler detects substantial exhaustion of filling. 110
15. In a loom, the combination of the lay, a shifting shuttle-box at each end of the lay having two cells, the upper cell at one side of the loom and the lower cell at the opposite side of the loom working with the same shuttle, a feeler at each side of the loom 115
- mounted to feel through the top of a shuttle and detect the condition of the filling when a shuttle is in the upper cell of a shuttle-box, and means for stopping the loom when either feeler detects substantial exhaustion of filling. 70
16. In a loom, the combination of the lay, a shifting shuttle-box at each end of the lay having two cells, the upper cell at one side of the loom and the lower cell at the opposite side of the loom working with the same shuttle, a feeler at each side of the loom mounted to feel through the top of a shuttle and detect the condition of the filling when a shuttle is in the upper cell of a shuttle-box, 80 and means common to the feelers at opposite sides of the loom for stopping the loom when either feeler detects substantial exhaustion of filling. 75
17. In a loom, the combination of the lay and shuttle boxes, a feeler mounted at each side of the loom to feel for the filling in the shuttle, slides movable longitudinally of the shuttle boxes as the lay is moved toward and from the front of the loom, means controlled 90 by the feelers for stopping the movement of the associated slide when the filling is substantially exhausted, and means for stopping the loom when either slide is stopped by a feeler. 95
18. In a loom, the combination of the lay, shifting shuttle-boxes at opposite sides of the lay having two cells for two shuttles, a feeler at each side of the loom, one of which detects the condition of the filling in one of the shuttles when it reaches one side of the loom, and the other of which detects the condition of the filling in the other when it reaches the other side of the loom, a sliding member adjacent each of the feelers moved 105 on each detecting beat, means connected to each feeler for arresting the movement of the adjacent sliding member when the filling is substantially exhausted, and means for stopping the loom when either sliding member is arrested. 110
19. In a loom, the combination of the lay and shuttle boxes, a feeler at each side of the loom, a slide at each side of the loom, means for imparting movement to the slides as the lay moves toward and from the front of the loom, a stop associated with each of the feelers adapted to be placed in the path of movement of the adjacent slide when the feeler detects substantial exhaustion of filling, and means for stopping the loom when either slide is arrested in its movements. 115
20. In a loom, the combination of a shipper lever, the lay and shuttle-boxes, two feelers, one at each side of the loom, and means between each of the feelers and the shipper lever for stopping the loom when either feeler at opposite sides of the loom detects substantial exhaustion of filling in a shuttle. 125

21. In a loom, the combination of the lay and shuttle boxes, a slide mounted for movement longitudinally of each of the shuttle boxes, means connecting the slides to a fixed part of the loom to cause said movement of the slides as the lay moves toward and from the front of the loom, a feeler at each side of the loom, and a stop movable by a feeler into

the path of movement of one of the slides when the feeler detects substantial exhaustion of filling, and means for stopping the loom when either slide is arrested. 10

In testimony whereof I have signed my name to this specification.

JAMES H. BARLOW.
